United States Patent Office.

JAMES K. DUGDALE, OF WHITE WATER, INDIANA.

Letters Patent No. 80,156, dated July 21, 1868; antedated July 15, 1868.

IMPROVED WASHING-MACHINE.

The Schedule referred to in these Letters Patent and making part of the same.

TO ALL WHOM IT MAY CONCERN:

Be it known that I, JAMES K. DUGDALE, of White Water, in the county of Wayne, and State of Indiana, have invented a new and useful Improvement in Washing-Machines; and I do hereby declare that the following is a full, clear, and exact description of the construction and operation of the same, reference being had to the annexed drawings, making a part of this specification, in which—

Figure 1 is a perspective view.

Figures 2 and 3, parts thereof.

Letter A, fig. 1, is a square frame, wide enough to admit any desired-sized wash-board, and about twice as high as wide. B and C are movable frames or gates, sliding between the upright posts of frame A, and guided by cross-pieces D D D D. Those on the inside may be thin boards, covering the whole frame, and sliding in grooves or rabbets in said upright posts. E is a wash-board, firmly fastened to frame A at an angle of about forty-five degrees, the front end about half way up the frame. Said board may be a common zinc board, or be composed of rollers. F is also a wash-board, is attached to the sliding frames B and C, and has rollers across the lower and upper ends, marked I, under which the clothes are thrust. The journals of the lower rollers pass through side-pieces N into frames B and C; those of the upper roller pass into said side-pieces.

J is a box-arrangement, containing a device for moving the pins a, which hold said board F to its position when shut, by pressing into orifices in gates B and C, or, when open, in orifices in frame A.

Illustrated by fig. 2, the covering of said box being removed, a a are the pins, extending nearly across the wash-board F, and through the side-pieces N, with shoulders to prevent their sliding too far out. b is a spiral spring, pressing against the rear of one of the pins. The pins are moved by turning knob K. A wire, c, passes through the journal of said knob, and is bent at right angles, and inserted in said pins at d. By turning knob K both pins are moved back, the spring pressing them out and fastening the wash-board F to its position. L is a frame wash-board or clothes-holder, in which the clothes are fastened, and is worked up and down between wash-boards E and F, and is composed of a frame, a sliding fluted board, to which a rod is attached. Said rod passes through a stationary cross-piece, in which is inserted an arrangement for fastening said sliding board down, thereby preventing the clothes from getting out of place. This arrangement is shown by fig. 3.

G is the frame. H, the movable fluted board. M, the stationary cross-piece. e, the rod, passing through said cross-piece. R, a knob, attached to the upper end of the rod e, by which the board H is moved. There are bevelled notches in rod e at f. g, a bolt, also bevelled to fit in notches at f, the notches and bolt being bevelled in opposite directions, to allow the sliding board to be pushed down by the handle or knob R, tightening the clothes in the holder, and fastening itself as pushed by means of the spring i pressing against the bolt g. h, a knob, attached to the bolt, which is pressed back while unfastening it, when the sliding board may be raised.

O O, fig. 1, are pulleys, over which cords m m pass, which cords are fastened to said pulleys near the handles P P. The other ends of said cords are attached to the gates B and C.

Q is a shaft, extending across frame A, through pulleys O O, and permanently fastened to said pulleys. P P are knobs or handles, attached to pulleys O O. By turning either pulley the pressure is regulated. S S are devices, composed of handles, journals, and spools, for the purpose of tightening the cords by which the machine is anchored to the vessel in which it may be used. n n are knobs, over which the cord is passed from said device.

I do not confine myself to any particular shape of wash-board, but may use plain fluted boards, or boards partly fluted and partly rollers, or all rollers, or straight or curved boards, as fancy or utility may demand.

I do not claim anew anything granted me in Letters Patent for "improved washing-machine," dated the 14th day of November, 1865, No. 50,922.

What I claim as my invention, and desire to secure by Letters Patent, is—

1. The knob K and wire c, in combination with pins a and spring b, as and for the purpose specified.
2. The bolt g, in combination with spring i, notches f, and clothes-holder L, as and for the purpose described.

JAMES K. DUGDALE.
